UNITED STATES PATENT OFFICE

164,424

PORTABLE GRANDSTAND UNIT

Joseph Huck, Tenafly, N. J., assignor to The Patent Scaffolding Co., Inc., Long Island City, N. Y., a corporation of New York

Application October 1, 1948, Serial No. 148,899

Term of patent 14 years

(Cl. D54—1)

To all whom it may concern:

Be it known that I, Joseph Huck, a citizen of the United States of America, residing at Tenafly, in the county of Bergen and State of New Jersey, have invented a new, original, and ornamental Design for Portable Grandstand Unit, of which the following is a specification, reference being had to the accompanying drawing, forming part thereof.

The figure is a perspective view of a portable grandstand unit showing my design.

I claim:

The ornamental design for a portable grandstand unit, substantially as shown.

JOSEPH HUCK.
